UNITED STATES PATENT OFFICE.

WILLIAM M. BACON, OF CHICAGO, ILLINOIS, ASSIGNOR TO E. S. KYLE, OF CHICAGO, ILLINOIS.

PRINTING MACHINE.

Application filed November 9, 1921. Serial No. 514,085.

To all whom it may concern:

Be it known that I, WILLIAM M. BACON, a citizen of the United States, residing at Chicago, Cook County, Illinois, have invented a new and useful Improvement in Printing Machines, of which the following is a specification.

This invention relates to printing presses.

An object of the invention is to provide a new and improved printing machine for producing two impressions or prints from a single application of paint to the forms supported on a form cylinder.

Another object of the invention is to provide a machine of novel and improved construction, having the parts arranged in a new cooperative relationship to obtain the desired results hereinafter set forth.

Another object of the invention is to provide a printing machine comprising a form cylinder mounted in a movable carriage, and improved means for controlling the cylinder to obtain proper results from the operation thereof.

Other objects will appear from the following description, reference being made to the accompanying drawing, in which—

Fig. 1 is a plan view of my improved machine.

Fig. 2 is a side elevation of the machine.

Fig. 3 is a vertical cross sectional view on the line 3—3 of Fig. 1.

In the embodiment shown, the frame of the machine comprises two parallel side members 1 secured to and supported by legs 2 and connected by transverse frame members 3 intermediate of the ends of the side members 1, and by transverse frame members 4 at or near the ends of the side members of the frame. The parts of the frame are rigidly united.

At the outer side of each of the frame members 1 a rail, comprising a support 5 and an angular track 6 secured to the support 5, is supported. The horizontal flanges of the angular tracks 6 extend from the upper edges of the supports 5 and the vertical flanges of the tracks extend downwardly against the outer sides of the supports 5.

The form impression cylinder 7 is supported for rotation in a longitudinally movable carriage operatively mounted on the

tracks described. As shown, the carriage 55 comprises two side members 8 located outside of the frame members 5 and supported by wheels 9 operating on the tracks. This arrangement permits the carriage to be moved back and forth as required in the 60 operation of the machine. The two side members 8 of the carriage are joined by connecting bars 10. Between the connecting bars 10 a pair of upright standards 11 rise from each side member 8 of the carriage, the standards 11 at each side being separated by a vertical space 12. A frame or box 13 is rigidly secured in the space 12 between each pair of standards 11, being retained in place by a plate 14 attached to 70 the upper ends of the standards. A journal bearing 15 is adjustably supported in each box frame 13 and is capable of vertical movements to different adjusted positions therein. The axial shaft 16 of the impression cylinder 7 is journaled for rotation in the bearings 15 so that by raising or lowering said bearings the form impression cylinder may be accurately positioned for 75 operation upon the work. Each journal bearing 15 is supported by a threaded rod or spindle 17 with which the bearings have swiveled connection of well known construction and arrangement. The spindles 17 are engaged in threaded holes in the plates 14 80 and have hand wheels 18 on their upper ends for manual engagement whereby the said spindles may be operated to raise or to lower the journal bearings 15 in order to effect accurate adjustment of the form 85 cylinder.

The forms may be secured to the cylinder in any satisfactory way, the form of attachment being immaterial to the present invention.

At each end of the form impression cylinder 7 a drum 19 is secured. The form cylinder and also the drums are rigid with the shaft 16 and, therefore, are relatively rigid. A rope or cable 20 is wound a number of 100 times around each of the drums 19, the ends of the rope or cable extending to the ends of the machine and thence to points of connection with proper parts of the machine. If desired, the ropes or cables 20 at the 105 ends of the machine may pass over sheaves or rollers 21. The ropes or cables are held from endwise movement so that when the

carriage is moved in either direction, the form cylinder in the carriage is necessarily rotated. The carriage may be moved back and forth by hand or otherwise as desired.

5 Between the center and one end of the frame a device for supporting the paint to be applied to the forms on the cylinder is mounted. As shown, said device comprises a slab 22 of slate or other appropriate material adapted to support the paint and serve as a palette. The carriage is moved to roll the form cylinder over the palette, the forms on the cylinder taking up the paint as the cylinder turns. It is sometimes desirable to

10 raise or to lower the palette to conform to the raised or lowered adjustment of the form cylinder. To permit such adjustment the palette is mounted on adjustable supporting spindles 23 equipped with hand wheels 24, whereby said spindles may be turned to raise and to lower the palette. The spindles 23 are operatively supported by the transverse frame members 3. This construction and arrangement will be readily understood

15 since it is the same as the arrangement by which the work table is supported and which will now be described.

The work table is adjustably supported between the center and the opposite end of the frame from the palette. As shown, the work supporting table comprises a number of wooden boards 25 arranged side by side to form a perfectly smooth upper surface and having their adjacent edges secured together by keys 26. The boards 25 are attached to transverse supports 27 which are vertically movable in order that the work supporting table may be adjusted properly with respect to the form cylinder. The supports 27 are carried by spindles 28 extending through the transverse frame members 3 and having threaded engagement with plates or blocks 29 mounted on said transverse frame members. The lower end of the spindles 28 are provided with hand wheels 30 whereby the spindles may be turned to raise or to lower the work supporting table.

As will be clearly understood by reference to Fig. 3, the drums 19 at the ends of the form cylinder 7 are concentric with the axis of the form cylinder and are of slightly larger diameter. The arrangement is such that when the forms are on the form cylinder they will operate properly upon the work when the form cylinder is rotated as an incident to the movement of the carriage 8.

In operation the paint is applied to the palette 22 by a brush or otherwise, and the carriage is moved to rotate the form cylinder above the palette, causing the forms to take up the paint. After paint has been applied to the forms, the carriage is moved in the opposite direction to cause the form cylinder to apply paint to the work upon the

work supporting table. The palette and the work supporting table may be adjusted relatively to each other and to the form cylinder; so also the form cylinder may be adjusted relative to the other parts.

70 From the foregoing it will be seen that my invention completely obtains all of its intended objects and purposes. The machine is of simple construction and arrangement and is efficient in operation. The parts may be easily adjusted as required in the character of work to be performed.

75 It is apparent that the construction and arrangement may be varied without departure from the nature and principle of the invention. I do not restrict myself unessentially, but what I claim and desire to secure by Letters Patent is: --

80 1. A printing machine, comprising a frame, a carriage mounted in the frame for back and forth movements, a plate for supporting the paint, means for supporting said plate in various adjusted positions, a work support in the frame, means for supporting the work support in different adjusted positions, and a rotary form cylinder mounted 85 in said carriage arranged to take paint from said plate and to apply the paint to the work on the work support.

90 2. A printing machine, comprising a supporting frame, a support for the work mounted in said frame, devices for raising and lowering said support in the frame, a palette for the paint, means for raising and lowering said palette in the frame, a carriage supported by the frame and movable back and forth thereon, a form cylinder journaled for rotation in the carriage, means for raising and lowering the form cylinder in different adjusted positions in the carriage, and means for rotating the form cylinder as an incident to movement of the carriage to take paint from said plate and to apply paint to the work on said work support.

95 3. In a machine of the character described, a work support, a carriage movable to and from the work support, a form cylinder in said carriage, a drum at each end of said carriage, a rope or belt passing a number of times around each of said drums, the ends 100 of said ropes or belts being secured to the frame, and means for supporting the form cylinder in different positions in the carriage.

105 4. In a machine of the character described, a work support, a carriage movable to and from the work support, a form cylinder in said carriage, a drum at each end of said carriage, a rope or belt passing a number of times around each of said drums, the ends 110 of said ropes or belts being secured to the frame, means for supporting the form cylinder in different positions in the carriage, and means for applying paint to the form cylinder as an incident to movement of the car- 115

riage and rotation of the form cylinder in directions toward and away from the work support.

5. In a machine of the character described, a frame, a flat work support in the frame, cross members in the frame, elements on the cross members having threaded holes therethrough, threaded spindles passing through said threaded holes and supporting the work support, means for operating said spindles to raise and to lower the work support, a carriage supported by the frame and being movable toward and away from the work support, a form cylinder journaled for rotation in the carriage, and means for raising and lowering the form cylinder in the carriage.

6. In a machine of the character described, a frame, a flat work support in the frame, cross members in the frame, elements on the cross members having threaded holes therethrough, threaded spindles passing through said threaded holes and supporting the work support, means for operating said spindles to raise and to lower the work support, a carriage supported by the frame and being movable toward and away from the work support, a form cylinder journaled for rotation in the carriage, means for raising and lowering the form cylinder in the carriage, and means for rotating the form cylinder as an incident to movement of the carriage.

7. In a machine of the character described, a frame, a flat work support in the frame, cross members in the frame, elements on the cross members having threaded holes therethrough, threaded spindles passing through said threaded holes and supporting the work support, means for operating said spindles to raise and to lower the work support, a carriage supported by the frame and being movable toward and away from the work support, a form cylinder journaled for rotation in the carriage, means for raising and lowering the form cylinder in the carriage, means for rotating the form cylinder as an incident to movement of the carriage, and means for applying paint to the form cylinder as an incident to movement of the carriage toward and away from the work support.

8. In a machine of the character described, a frame, a work support in the frame, a carriage movable to and from the work support, a form cylinder journaled for rotation in the carriage, a drum at each end of the carriage, and ropes or belts passing around said drums and extending to fixed connections at opposite ends of the frame.

9. In a machine of the character described, a frame, a work support between the center and the opposite end of the frame, a carriage movable back and forth on the frame, means for raising and lowering the work support and the paint palette in the frame, a cylinder journaled for rotation in the carriage, and means for rotating said cylinder as an incident to movement of the carriage in either direction.

10. In a machine of the character described, a frame, a work support between the center and one end of the frame, a palette between the center and the opposite end of the frame, a carriage movable back and forth on the frame, a form cylinder supported for rotation in the carriage, drums having a larger diameter than the cylinder mounted in fixed connection with the cylinder, and ropes or belts passing around said drums respectively and having their ends secured to the frame.

11. In a machine of the character described, a frame, a flat work support in the frame, cross members in the frame, elements on the cross members having threaded holes therethrough, threaded spindles extending vertically through said threaded holes and supporting the work support, means for turning said spindles to raise and to lower the work support, a rail at each side of the frame, a carriage operatively supported by said rails and being movable toward and away from the work support, a form cylinder in the carriage, and ropes or belts for rotating the form cylinder as an incident to movement of the carriage.

12. In a machine of the character described, a frame, a flat work support in the frame, means for raising and lowering the work support, a carriage supported by the frame and being movable toward and away from the work support, a form cylinder in the carriage, and ropes or cables for rotating the form cylinder in the direction in which the carriage moves as an incident to the movement of the carriage in either direction.

13. In a machine of the character described, a frame, a palette in the frame, a work support in the frame, means for raising and lowering the palette and the work support independently of each other, a carriage supported by the frame, a form cylinder in the carriage, and ropes or cables for rotating the form cylinder in the direction in which the carriage moves as an incident to the movement of the carriage.

WILLIAM M. BACON.
